AUTOMATIC ANNUNCIATOR

Lang Jung Sing and Robert M. Waunch,
Salem, Oreg.

Application January 26, 1935, Serial No. 3,619

3 Claims. (Cl. 274—15)

This invention relates to automatic annunciators, and is particularly adapted to advertising and alarm systems. Our new and improved annunciator consists of a mechanism for announcing a predetermined recording or recordings through an amplifying set, into a loud speaker, public address system or other suitable receiving set.

The beginning of a cycle of operation is commenced by interrupting an invisible light ray which is constantly being directed to a photo-electric cell, either directly from a light source or indirectly through a system of mirrors changing the direction of the light ray from the source to the photo-electric cell.

The electric reaction developed within the photo-electric cell, by the interruption of the invisible light ray, is amplified sufficient to operate an electric relay, this relay closes an electric circuit causing a solenoid to bring into operating position a pick-up mechanism transferring a recording from a record to an amplifying set thence to the loud speaker, public address system or other suitable receiving set.

In the operation of our invention in relation to advertising, the loud speaker can be stationed at any desired location. The invisible light ray is directed across the path to be traversed by the person or subjects, the momentary interruption of the ray immediately setting the annunciator into operation broadcasting the desired advertising or information.

In the event that our annunciator is to be used as a burglar alarm system, the invisible rays would be directed across all entrances to the building and in such cross-sectional shape that they would be sure to be interrupted setting the annunciator into operation either notifying a central station of the entry or broadcasting on the immediate premises.

It will be readily understood that there are many uses to which our invention can be readily adapted to besides the applications just mentioned above.

Other, further and additional objects of the invention will be readily seen upon reading the description thereof, aided by the accompanying drawings, wherein:—

Figure 1 is a diagrammatical layout of the units making up our new and improved automatic annunciator, the purpose of this view is to illustrate the location of the annunciator, the invisible light ray producing unit employing mirrors to change the direction of the ray so as to

surround a given point with a ray, before it reaches the photo-electric cell unit.

Figure 2 is a side elevation of the photo-electric cell unit partially broken away for convenience of illustration.

Figure 3 is a side elevation partially broken away illustrating the invisible light producing ray unit.

Figure 4 is a diagrammatical layout including the light ray producing unit, a mirror reflecting the light ray in another direction, the photo-electric cell receiving the ray, the amplifying unit and the relay switch for throwing the address system into operation.

Figure 5 is a diagrammatical layout of the pick-up mechanism associated with the recorded subject matter to be broadcast, the loud speaker and the amplifying unit connected therewith.

Figure 6 is a plan view of the record, pick-up arm, and our new and improved mechanism for controlling the operation of the pick-up and reproducing arm.

Figure 7 is a side elevation of the above mechanism.

Figure 8 is a plan view of the above mechanism showing the pick-up arm just as it is finishing the subject matter contained on the record and ready to be returned to a starting position.

Figure 9 is a fragmentary sectional end-view of a part of the mechanism for returning the pick-up arm to a starting point.

Referring to the drawings, we have shown a station or building 1, a sidewalk 2 is shown passing in front of the building. A curb entry 3 connects the sidewalk with the curb. The invisible light ray producing mechanism is illustrated at 4 producing a light ray 5 reflecting it on a mirror 6 thence to another mirror 7 directing it into the photo-electric cell unit 8. It can be seen that any person walking by on the sidewalk 2 will interrupt the light rays directed into the photo-electric cell unit 8 or coming directly into the entry 3 will also interrupt the light ray. The loud speaker is stationed at 9, the amplifying unit is indicated at 10. In some cases using our system of announcing there may not be any loud speaker as a receiver may be stationed at a distant point for receiving the signal from the amplifier 10.

Referring to Figure 2 the photo-electric cell 11 is mounted within the case 12 and is surrounded by a shield 13 and an adjustable lens 14 is mounted within the tube 15. The tube 15 being adjustable longitudinally within the tube 16. An

amplifying unit partially shown at 17 is also located within the case 12.

Figure 3 is a side elevation of the ray producing unit having a reflector 18 mounted therein receiving its source of invisible ray from the globe 19 reflecting the same out through the lens 20 as above referred to.

In Figure 4 the ray producing unit is shown as 21 directing a ray 22 to mirror 23 into the photo-electric cell 11 an electric reaction takes place within this cell and is amplified by the amplifying unit 24 which consists of the rectifying and positive current supply unit 24a, having a positive current connection 24b which is connected to the plate of the amplifying tube 24c. The electrodes of the photo-electric cell 11 are connected respectively to ground and control grid of tube 24c operates the relay switch 25 in series with the positive supply 24b, thus closing the electric circuit from the transformer 26. Figure 5, conductor 27, switch bar 28, conductor 29 solenoid 30, back to the transformer by conductor 31. Solenoid 30 draws the core 32 down pulling the end 33 of the bar 34 down, the bar 34 being pivotally mounted at 35 raises the end 36 lifting the pin 37 away from the V-shape trough 38 permitting the pick-up bar 39 to be lowered to the record 40. The pick-up bar 39 is pivotally mounted on the pedestal 41, in a well-known manner. The turntable 42, which is rotated by a conventional electric motor, not shown, is in constant rotation so that when the pick-up bar needle 43 contacts the record 40 the reproduction will take place immediately. A switch bar 44 mounted to the end 45 of the pick-up bar and insulated therefrom engages the electric terminal 46 closing an electric circuit from the transformer 26, conductor 47, switch bar 44, terminal 46, conductor 48, conductor 29, solenoid 30 and conductor 31 to transformer 26. The object of this last circuit is to continue the energizing the solenoid 30 after the photo-electric cell had momentarily energized the solenoid, in other words this circuit is a locking circuit. Referring to Figure 8 when the pick-up arm has completed the subject matter to be broadcast from the record, the switch bar 44 breaks contact with the terminal 46, breaking the locking circuit, allowing the solenoid 30 to become demagnetized. The interval of engagement of the bar 44 with terminal 46 may be hastened or delayed. This is accomplished by providing a slot 46a in the base of member 46. This slot rides upon the screw 46b to which is threaded a nut 46c. By tightening the nut on the screw member 46b, member 46 is held against movement. However by loosening the nut member 46 may be moved back and forth, or pivoted on screw 46b. This allows member 46 to be positioned to or from member 44 thereby hastening or delaying their engagement relative to the time interval of reproduction from a record. The spring 49 pulls the end 36 of the bar 34 downward, referring to Figure 9, the pin 37 contacts the incline surface 50 of the trough 38 which will raise the point 43 carried by the pick-up arm 39 out of contact with the record 40 at the same time forcing the end 45 of the pick-up arm to the right as indicated by the arrow in Figure 9 which will swing the opposite end of the pick-up arm towards the beginning of the record. The spring 49 will continue to hold the pick-up arm out of engagement with the record until the invisible ray is again broken, setting up another complete cycle of operation. Adjustments

51 and 52 are provided for adjusting the stopping points of the pick-up arm at the position of rest.

The usual leads 53 connect the pick-up arm with the input of the amplifier 54 which is connected with the loudspeaker coil 55. An amplifier unit, which is of the conventional type, consists of the rectifying unit 54a; and also comprises the input 53, amplifying tubes 54b, intermediate transformers 54c, and output transformer 54d 10 which is connected to the voice coil 55 of speaker 8.

From the foregoing it can be readily seen that the momentary breaking of the invisible ray starts the broadcasting of the desired information after which the machine is locked in operating position until the information has been broadcast, a secondary breaking of the photo-electric ray will not in any way affect this cycle of operation after it has once been set into effect. 20

We do not wish to be limited to this particular form of construction as our invention is susceptible to other forms of embodiment still coming within the scope of our invention as hereinafter claimed. 25

Having described our invention, we claim:—

1. In an annunciator system, the combination of a record reproduction means including a pickup, a rocking member engaging the reproduction means and moving it from a position terminating the reproduction of a record to a position to commence the reproduction of a record, an electromagnetic device connected to the rocking member operable when energized to move the rocking member to a position disengaging the reproduction means, a circuit momentarily energizing the electromagnetic device, an electric switch closed by the reproduction means, and a holding circuit in series with the electromagnetic device and said switch. 40

2. An annunciator system, the combination of a record reproduction means including a pickup, a rocking member engaging the reproduction means and moving it from a position terminating the reproduction of a record to a position to commence the reproduction of a record, an electromagnetic device connected to the rocking member operable when energized to move the rocking member to a position disengaging the reproduction means, a circuit for momentarily energizing the electromagnetic device, an electric switch closed by the reproduction means during the period of reproduction, means for adjusting the switch to alter the period of opening and closing, and a holding circuit in series with the electromagnetic device and the switch. 45

3. An annunciator system, the combination of a record reproduction means including a pickup, a pivoted bar, means urging the bar to normally engage the reproduction means and move it from a position terminating the reproduction of a record to a position to commence the reproduction of a record, an electromagnetic device connected to the bar operable when energized to move the bar against the action of the urging means to a position disengaging the reproduction means, a circuit for momentarily energizing the electromagnetic device, an electric switch closed by the reproduction means during the period of reproduction, and a holding circuit in series with the electromagnetic device and the switch. 70
